(57) **CLAIM**

The ornamental design for a holder for a mobile electronic device, as shown and described.

DESCRIPTION

FIG. 1 is an upper side view of the holder for a mobile electronic device in accordance with a first embodiment of the invention.

FIG. 2 is a front view of the holder for a mobile electronic device in accordance with the first embodiment of the invention.

FIG. 3 is a left side view of the holder for a mobile electronic device in accordance with the first embodiment of the invention.

FIG. 4 is a right side view of the holder for a mobile electronic device in accordance with the first embodiment of the invention.

FIG. 5 is a lower side view of the holder for a mobile electronic device in accordance with the first embodiment of the invention.

FIG. 6 is a rear view of the holder for a mobile electronic device in accordance with the first embodiment of the invention; and,

FIG. 7 is a front upper-side perspective view of the holder for a mobile electronic device in accordance with the first embodiment of the invention.

(Continued)

The broken lines represent portions of the structure that forms no part of the claim.
